United States Patent Office

Des. 182,947
Patented June 3, 1958

182,947

BALANCE SCALE

Harry C. Becker, New Rochelle, N. Y.

Application March 14, 1956, Serial No. 40,608

Term of patent 3½ years

(Cl. D52—10)

Fig. 1 is a perspective view of the balance scale showing my new design.

Fig. 2 is a side view of the balance scale.

The essential features of the design reside in the case shown in full lines.

I claim:

The ornamental design for a balance scale, as shown and described.
